Primary Examiner — Katrina A Betton(74) *Attorney, Agent, or Firm* — Donald L. Schoonover(57) **CLAIM**

I claim the ornamental design for a compact swivel unit with pin-less stowing lobes for a tow bar, as shown and described.

DESCRIPTION

This application is being filed concurrently with utility patent application Ser. No. 13/385,046.

FIG. 1 is a perspective view of a compact swivel unit with pin-less stowing lobes for a tow bar showing my new design; the broken lines in FIGS. 1 and 8 depict environmental structure for illustrative purposes only and form no part of the claimed design;

FIG. 2 is a top plan view thereof;

FIG. 3 is a bottom plan view thereof;

FIG. 4 is a side elevational view thereof;

FIG. 5 is an elevational view of the opposing side thereof;

FIG. 6 is a front elevational view thereof;

FIG. 7 is a rear elevational view thereof; and,

FIG. 8 is a perspective view thereof in a stowed configuration.
